DESIGN.

M. SLOTKIN.
LEG BRACE, &c.

UNITED STATES PATENT OFFICE.

MAYER SLOTKIN, OF NEW YORK, N. Y.

DESIGN FOR A LEG-BRACE, &c.

SPECIFICATION forming part of Design No. 27,460, dated August 3, 1897.

Application filed May 11, 1897. Serial No. 836,108. Term of patent 14 years.

To all whom it may concern:

Be it known that I, MAYER SLOTKIN, a citizen of the United States, residing in the city, county, and State of New York, have invented 5 and produced a new and original Design for Machine Leg-Braces and Shaft-Supports, of which the following is a specification, reference being had to the accompanying drawings.

Figure 1 of the drawings shows a plan view of my design. Fig. 2 shows a longitudinal elevation of the same, looking in the direction indicated by the arrows *x* in Figs. 1, 3, and 4. Fig. 3 shows a side or end elevation of the 15 same, looking in the direction indicated by the arrows *y* in Figs. 1 and 2. Fig. 4 is a side elevation of the same, looking in a direction indicated by the arrows *z z* in Figs. 1 and 2.

The leading features of my design are the 20 machine leg-brace and support having the overhanging bracket portions A, the connecting-arch B, and the panel-shaped portion C. The overhanging bracket portion A is composed of the projecting arms *a* and the longitudinal connection *a²*. These portions are 25 stiffened, as shown in the figures, by the inter-reaching arch B, connecting uprights *a³*, at the ends of which the shaft bosses or bearings

D^x are located. The panel portion C is formed by sides *c', c¹, c³, and c²*, the latter being formed 30 integrally with the leg-brace design or by the machine-leg itself. The end views, Figs. 3 and 4, are alike in appearance, but are right and left with each other.

The projecting arms (best shown in Figs. 35 3 and 4) are designed to carry the shaft-bearing portions D. The up-and-down projecting portions *d', d², d³, and d⁴* are designed to attach the machine-legs to for security and rigidity. 40

A careful examination and comparison of the several figures will readily convey the nature of the peculiar and distinctive machine leg-brace design, similar letters of reference designating like parts or portions in all the 45 figures.

What I claim as new, and desire to secure by Letters Patent, is—

The design for a machine leg-brace and shaft-support substantially as herein shown 50 and described.

MAYER SLOTKIN.
